UNITED STATES PATENT OFFICE.

MARSHALL F. HOBSON AND WILLIAM H. MOORE, OF OAKLAND, CALIFORNIA.

DESIGN FOR AN EGG COOKER.

Application filed April 7, 1926. Serial No. 17,213. Term of patent 14 years.

To all whom it may concern:

Be it known that we, MARSHALL F. HOBSON and WILLIAM H. MOORE, citizens of the United States, residing at Oakland, county of Alameda, and State of California, have invented a new, original, and ornamental Design for an Egg Cooker, of which the following is a specification, reference being had to the accompanying drawing, forming part thereof.

The figure is a perspective view of an egg cooker showing our new design.

We claim:—

The ornamental design for an egg cooker as shown.

MARSHALL F. HOBSON.
WILLIAM H. MOORE.
